REED FOR SAXOPHONES, CLARINETS, AND
LIKE WIND INSTRUMENTS

Mario Maccaferri, Paris, France

Application October 23, 1934, Serial No. 749,639
In Great Britain October 25, 1933

4 Claims. (Cl. 84—383)

The present invention relates to reeds for saxophones, clarinets or like wind instruments and it has for its principal object to provide a reed having improved properties whereby its vibration, control and retention of shape are improved.

Heretofore, reeds have been made from cane or like natural products by cutting a length therefrom in a direction extending substantially parallel to the axis of the cane, one end of the cut piece being tapered off to a pointed edge along a plane disposed obliquely to the principal axis of the cut piece. As the grain or fibre of the cut piece extends parallel to the outer faces thereof and as the tapering part thereof cuts across the grain, the said grain is more exposed on the side of the reed which is cut away to form the tapered edge than on the other side of the reed and this leads to distortion and lack of symmetry in vibration, whereby purity of tone is impaired.

In accordance with the invention a reed for a saxophone, clarinet or the like is formed from cane or the like by cutting a piece therefrom in a direction extending obliquely to the fibres or diagonally to the axis of the cane, whereby the fibres are exposed symmetrically on the two sides of the pointed edge subsequently formed on said piece and of which the pointed edge constitutes the active or vibrating part.

By virtue of this arrangement, a more symmetrical vibration is obtained and the reed is less liable to be distorted by absorbing moisture from the mouth.

The invention will be more fully described hereinafter with reference to the accompanying drawings, in which:—

Fig. 1 shows a length of cane and the manner in which the new reed in accordance with the invention is cut therefrom.

Fig. 2 is an end view of the reed showing in dotted lines the length of cane from which the reed is cut, and

Fig. 3 is a view similar to Fig. 1 showing the improved reed according to the invention.

As shown in Fig. 1 the reed according to the present invention is cut on the bias from a length of cane 2 in a direction oblique to the axis of said length of cane. There is indicated in dotted lines at 3 on the figure a central longitudinal section showing the manner in which the reed is cut while Fig. 2 gives an end view showing the reed

4 and, in dotted lines, a part of the length of cane 2 from which the reed is cut.

As shown in Fig. 3, the reed 4 is finished off by forming a tapered end portion 1 thereon. However, owing to the fact that the length 4 is cut diagonally across the grain, the said grain is exposed symmetrically on the two sides of the tapered portion 1. As a consequence of this arrangement, the reed is less liable to distortion from absorbed moisture while the vibration is more symmetrical than is the case with the known reeds. In Fig. 3 the direction of the grain of the fibres is indicated in dotted lines and it is clearly seen that this grain is exposed symmetrically on the two sides of the tapered portion 1 as indicated above.

The invention is not limited to the precise forms or details of construction described, as these may be varied to suit particular cases.

What I claim and desire to secure by Letters Patent of the United States of America is:—

1. A reed for a wind-instrument having a vibratile tip portion tapering to a pointed edge, the fibres extending symmetrically on the two sides of said tapering portion.

2. A reed for musical wind-instruments comprising a section of cane taken on the bias or slightly diagonally to the longitudinal direction of the fibres of the cane, and having a vibratile tip portion, the fibres of the cane extending symmetrically on the two sides of said vibratile portion.

3. A reed for musical wind-instruments comprising a section of cane taken in a direction extending diagonally away from the axis of the cane, and composed of a body part and a vibratile part, the latter being tapered and the fibres of the cane extending symmetrically on the two sides of said tip part.

4. A reed for musical wind-instruments composed of a section of cane and including a body portion having parallel faces and a tapered tip portion located at one end of said body portion, said section being tapered off to a pointed edge along a plane oblique to said parallel faces, said parallel faces being oblique to the direction of the fibres of the cane so that the fibres are exposed symmetrically on the two sides of the tapered tip portion.
